DESIGN FOR A BADGE.

SPECIFICATION forming part of Design No. 34,650, dated June 11, 1901.

Application filed May 13, 1901. Serial No. 60,123. Term of patent 7 years.

To all whom it may concern:

Be it known that I, PHILIP ZEHNER, Jr., a citizen of the United States, residing at Colorado Springs, in the county of El Paso and State of Colorado, have invented and produced a certain new and original Design for Badges, of which the following is a specification, reference being had therein to the accompanying drawing.

10 My invention relates to a new and original design for badges, the object being the production of a badge of ornamental and attractive appearance which will serve its purpose as an ornament as well as a symbol.

15 With this object in view my invention consists of the design illustrated in the accompanying drawing and described in the following specification.

20 I have shown in the drawing a front view of my design on an enlarged scale.

The design consists of the representation of the clock or dial A, on each side of which extends the base or ground representation B, upon which and above the dial is the representation of a running elk C, and extending above the elk is the representation of the tree D, the whole forming a design of beauty and also making an attractive and useful symbol. ²⁵

I claim—

The design for a badge, substantially as ³⁰ herein shown and described.

In testimony whereof I affix my signature in presence of two witnesses.

PHILIP ZEHNER, JR.
